DOUBLE DECK BED

James C. Bouffard, High Point, N.C., assignor to Mohasco Industries, Inc., Amsterdam, N.Y., a corporation of New York

Filed Jan. 24, 1969, Ser. No. 15,484

Term of patent 14 years

Int. Cl. D6—01

U.S. Cl. D5—4

The single figure is a side, top and end perspective view of a double deck bed, showing my new design, the opposite side and end being substantially a mirror image thereof.

I claim:

The ornamental design for a double deck bed, substantially as shown and described.
